WRITING IMPLEMENT

Murray Fields, New Rochelle, N.Y., assignor, by mesne assignments, to Consolidated Food Corporation, Chicago, Ill., a corporation of Maryland

Filed Nov. 4, 1966, Ser. No. 4,557

Term of patent 14 years

U.S. Cl. D74—17

Int. Cl. D19—06

FIG. 1 is a perspective view of a writing implement showing one form of my new design;

FIG. 2 is a side elevational view of the form of writing implement shown in FIG. 1;

FIG. 3 is a top plan view of the form of writing implement shown in FIG. 1;

FIG. 4 is a bottom plan view of the form of writing implement shown in FIG. 1;

FIG. 5 is a sectional view taken along the lines 5—5 of FIG. 2;

FIG. 6 is a rear elevational view of another form of the writing implement shown in FIG. 1, being identical to the form of design shown in FIG. 1 with the exception that the truncated portion below the upper operating tip is plain and does not have the ornamentation of the first form of invention; and

FIG. 7 is a top plan view of the form of design for a writing implement as shown in FIG. 6.

The dominant features of my design reside in the portions shown in full lines, a conventional writing tip portion being shown in broken lines in FIGS. 1, 2, 4, and 6.

I claim:

The ornamental design for a writing implement, substantially as shown and described.
